UNITED STATES PATENT OFFICE

J. CHARLES F. ATSATT, OF MATTAPoisETT, MASSACHUSETTS.

DEVICE FOR AUTOMATICALLY REGULATING COMBUSTION IN HOT-WATER AND HOT-AIR HEATING APPARATUS.

SPECIFICATION forming part of Letters Patent No. 406,018, dated July 2, 1889.

Application filed February 21, 1889. Serial No. 300,968. (No model.)

To all whom it may concern:

Be it known that I, J. CHARLES F. ATSATT, a citizen of the United States, residing at Mattapoisett, in the county of Plymouth and State 5 of Massachusetts, have invented certain new and useful Improvements in Devices for Automatically Regulating Combustion in Hot-Water and Hot-Air Heating Apparatus, of which the following is a specification.

10 The object of my invention is to provide an automatic regulator of combustion in hot-water and hot-air heating apparatus, which will be sensitive to a great variety of temperatures, simple and durable in construction, easily and quickly attachable to the heating apparatus, and one which can be afforded to the consumer at a comparatively slight expense.

To this end my invention consists in an 15 air-chamber adapted to be clamped or otherwise attached to a hot-water or hot-air heating apparatus and provided with a flexible diaphragm and mechanism intermediate between said diaphragm and the damper or 20 draft-opening of said heating apparatus, whereby the expansion and contraction of the air in said chamber are caused to regulate said damper or draft-opening.

In the accompanying drawings, Figure 1 25 represents a view of my invention clamped to the main pipe of a hot-water heating apparatus. Fig. 2 is a view in vertical section of the same. Fig. 3 represents an elevation of a heating apparatus with my invention attached.

Similar letters refer to similar parts in the several views.

b represents a hollow chamber for containing air, which may be of any convenient 30 form, best adapted for attaching to the heating apparatus. In this instance it has a concave side to fit the curve of the pipe to which it is clamped.

a represents a section of the main pipe of 35 a hot-water heating apparatus, to which the chamber b is secured by the clamp e. The chamber b is provided with the stop-cock p, in order that it may be charged with more than one atmosphere, if desired. The chamber b is also provided with a flexible dia-

phragm h, secured to and making an airtight joint with the top or mouth of the broad shallow bowl i. The side of the bowl is provided with the standard f, to the top of which is pivoted one end of the lever l, the other 55 end being provided with the weights w. The pillar g rests on the diaphragm h, with its top bearing against the under side of the lever l. d is a wire connecting the lever l with the damper or draft-opening of the heating apparatus.

The operation of my invention is as follows: The air-chamber b, with its attachments, is clamped or otherwise attached to some convenient part of the heating apparatus in such a manner that a considerable portion of its surface shall come in close contact with the surface of the heating apparatus, and the lever l connected with the damper or draft-opening. When the temperature of the heating apparatus has risen to a certain degree, the air in the chamber has expanded sufficiently to swell the diaphragm h outwardly, and thus by means of the intermediate mechanism regulate the 60 damper or draft-opening. If it is desired to regulate the temperature of the heating apparatus to a lower degree, some or all of the weight w is removed from the end of the lever l, when it is obvious that a less expansive 65 force of the air in the chamber will cause the damper or draft-opening to be regulated. If it is desired to regulate the temperature to a still lower degree, the chamber is charged 70 through the stop-cock p with more than one 75 atmosphere, when a very moderate degree of heat will cause the dense air in the chamber to expand sufficiently to expand the diaphragm, and thus regulate the draft.

Thus it will be seen that by the use of an 80 air-chamber the device is rendered extremely sensitive to even moderate temperatures.

Having thus described my invention, what I 85 claim, and desire to secure by Letters Patent, is—

A device for automatically regulating combustion in hot-water and hot-air heating apparatus, consisting of the air-chamber b, having one of its sides concaved to conform to the convex surface of the main pipe of said 90 95 100

apparatus and adapted to be clamped thereto, and provided with the cock *p*, in combination with the bowl *i*, connected with said air-chamber and provided with flexible diaphragm *h*,
5 and mechanism intermediate between said diaphragm and the damper or draft-opening of said heating apparatus, whereby the expan-

sion and contraction of the air in said air-chamber closes or opens said damper or draft-opening, all as shown and described.

J. CHAS. F. ATSATT.
